Patented Aug. 26, 1975

236,523

TOY TRAIN

Victor G. Reiling, East Aurora, N.Y., assignor to The
Quaker Oats Company, Chicago, Ill.

Filed Dec. 20, 1973, Ser. No. 426,519

Term of patent 14 years

Int. Cl. D21—01

U.S. Cl. D34—15 MM

FIG. 1

FIG. 5

FIG. 4

FIG. 3

FIG. 1 is a perspective view of a toy train showing my new design and comprising a locomotive, a gondola car, a cage car, and a caboose;

FIG. 2 is a bottom plan view thereof on a slightly enlarged scale with the locomotive at the right and the caboose at the left;

FIG. 3 is a rear elevation of the locomotive;

FIG. 4 is a rear elevation of the caboose;

FIG. 5 is an elevation of the side of the cage car that is hidden in FIG. 1;

FIG. 6 is a rear elevation of the gondola car; and

FIG. 7 is a rear elevation of the cage car.

I claim:

The ornamental design for a toy train, substantially as shown and described.
